UNITED STATES PATENT OFFICE.

MAX C. MILLER, OF CUMBERLAND HILL, RHODE ISLAND, ASSIGNOR TO JENCKES KNITTING MACHINE COMPANY, OF PAWTUCKET, RHODE ISLAND, A CORPORATION OF RHODE ISLAND.

DRIVING MECHANISM FOR KNITTING MACHINES.

Original application filed April 5, 1921, Serial No. 458,640. Divided and this application filed May 27, 1922. Serial No. 564,207.

The invention relates to driving mechanism for that class of knitting machines in which a rotary knitting element such as a needle cylinder or cam cylinder is given a continuous rotary movement at times and a reciprocatory movement at other times during the knitting.

The object of the invention is to provide a simple and efficient mechanism for driving the rotary knitting element and for shifting from one motion to the other with certainty and without shock or undue wear upon the parts and to these ends the invention comprises the features of construction and combination of parts hereinafter described and referred to in the claims.

A mechanism embodying a preferred form of the invention is shown in the accompanying drawings in which Fig. 1 is a vertical sectional view; Fig. 2 is a transverse sectional elevation on line 2 of Fig. 1, and Fig. 3 is a perspective view of the ring 36 to be described.

The invention is shown in the drawings applied to a circular knitting machine fully shown and described in application Serial No. 458,640, filed April 5, 1921, of which the present application is a division. This machine is provided with a rotary needle cylinder 2 carrying needles 4 which are operated by cams and controlling devices carried by a stationary cam cylinder 6. The needle cylinder is carried on and connected to rotate with a gear 8. The gear is mounted to rotate within a vertically movable ring 10 provided with ribs 12 which rest upon supporting rolls 14 and are held in engagement therewith by rolls 16. The cylinder is rotated and reciprocated through a gear 18 which engages the gear 8 and is secured upon the upper end of a short vertical shaft 20. The lower end of the shaft is connected through a beveled gear 22 with a beveled gear 24 which is formed on the end of a sleeve 26 loosely mounted on the driving shaft 27.

A motion changing clutch sleeve 28 is keyed to slide on the sleeve 26 and may be shifted to connect the sleeve 26, and therefore the needle cylinder, with either a continuously rotating pinion 29 or an oscillating pinion 30. The rotary pinion 29 is pinned to the shaft 27 while the oscillating pinion

30 is loosely mounted on the sleeve 26. The oscillating pinion is driven through an oscillating segment 31 connected by a link 32 with a crank pin 33 on a gear 34, which meshes with the rotary pinion 29, the gear being four times the diameter of the pinion so that it makes one revolution for four revolutions of the driving shaft. The clutch sleeve 28 is provided at each end with a projecting clutch tooth, one of which is adapted to engage a recess in the side of pinion 30 and the other to engage a recess in the side of the pinion 29.

The mechanism for shifting the clutch to change the motion of the needle cylinder from rotary to reciprocating, or from reciprocating to rotary, comprises two cam rings 35 and 36 adjustably secured on opposite ends of the clutch sleeve and two radially movable pins 37 and 38. Each cam ring is provided with an inclined cam surface 39 adapted to engage the corresponding pin 75 and to shift the clutch from one pinion to the other. The clutch shifting pins are automatically raised and lowered and are spring-pressed so that they will ride on the cam ring when free to do so. After the active pin has cooperated with the corresponding cam ring to shift the clutch it moves down inside the ring and acts to lock the clutch in shifted position. As shown the pin 38 is in clutch-locking position and holds the clutch in engagement with the rotary pinion 29 while the pin 37 is raised and held in inactive position. When the motion is to be changed from rotary to oscillating the pin 38 is raised and the pin 37 is released so that it 90 rides on the cam ring 35 until the inclined surface 39 on this ring engages the side of the pin and shifts the clutch to the right and into engagement with the oscillating pinion 30. The incline 39 is so located that 95 the clutch is shifted while the tooth on the end of the clutch sleeve is in register with the recess in the pinion 30 and the clutch is quickly and positively shifted from the rotary to the oscillating pinion. As the shifting of the clutch is completed the pin 37 moves down back of the ring 35 and locks the clutch in shifted position. When the motion is to be again changed from oscillating to rotary the pin 37 is raised and the pin 38 105 released so that the clutch is positively

shifted in a similar manner by the engagement of the incline 39 on cam ring 36 with the pin 38 and is locked by the pin as indicated in Fig. 1.

5 The clutch controlling pins 37 and 38 are alternately raised and lowered at proper intervals through two levers 40 and 41, mounted on the stud 17'. The forward ends of the levers underlie studs 42 projecting from 10 the clutch pins and the rear ends of the levers are arranged to bear on cams 43 carried on the pattern shaft 44 which is intermittently moved during the knitting at proper intervals by a suitable actuating mechanism 15 (not shown).

While it is preferred to employ the specific construction and arrangement of parts shown and described in embodying the invention in the machine indicated in the drawings it will be understood that this construction and arrangement is not essential to the broader features of the invention and may be varied or modified as found desirable or best suited to the mode and construction of 25 the machine to which the invention is applied.

What is claimed is:

1. A machine having, in combination, a 30 rotary element, actuating mechanism therefor, comprising rotating and oscillating clutch members, a motion changing clutch sleeve provided with cams for shifting it from one clutch member to the other, cooperating pins movable into and out of the path of the cams and pattern mechanism for moving the pins.

2. A machine having, in combination, a rotary element, actuating mechanism therefor, comprising rotating and oscillating clutch members, a motion changing clutch sleeve provided with oppositely acting cams for shifting it from one clutch member to the other, cooperating controlling pins, and pattern mechanism for alternately advancing and retracting the pins.

3. A machine having, in combination, a 50 rotary element, actuating mechanism therefor, comprising rotating and oscillating clutch members, a motion changing clutch sleeve, two cam rings on the clutch sleeve, pins for alternately cooperating with the rings to shift the clutch sleeve and lock it in shifted position and pattern mechanism for actuating the pins.

4. A machine having, in combination, a 55 rotary element, actuating mechanism therefor, comprising rotating and oscillating clutch members, a motion changing clutch sleeve between said members, two cam rings, 60 two pins arranged to alternately ride on the corresponding rings to shift the clutch sleeve and to advance inside the rings to lock the clutch sleeve in shifted position, and

means for alternately advancing and retracting the pins.

5. A machine having, in combination, a 65 rotary element, actuating mechanism therefor, comprising rotating and oscillating clutch members, a motion changing clutch sleeve, a ring on each end of the sleeve having an inclined cam surface on its periphery, two pins so arranged that one is in position to pass inside one ring when the clutch sleeve is in engagement with one clutch member, and the other is in position to pass inside the other ring when the clutch sleeve is in engagement with the other clutch member, and means for advancing and retracting the pins.

6. A machine having, in combination, a 70 rotary element, actuating mechanism therefor, comprising rotating and oscillating clutch members, a motion changing clutch sleeve, a ring on each end of the sleeve having an inclined cam surface on its periphery, 75 two spring pressed pins arranged to ride on and pass inside of the corresponding rings, and means for alternately retracting and releasing the pins.

7. A machine having, in combination, a 80 rotary element, actuating mechanism therefor, including a motion changing clutch sleeve, cams on the sleeve and pins radially movable in fixed bearings cooperating with the cams to alternately shift the clutch 85 sleeve in opposite directions, and a pattern mechanism for moving the pins.

8. A machine having, in combination, a 90 rotary element, actuating mechanism therefor comprising two clutch members, a clutch 100 sleeve between the clutch members, cams on the clutch sleeve, and pins radially and independently movable in fixed bearings cooperating with the cams to alternately shift the clutch sleeve in opposite directions and 105 pattern mechanism for moving the pins.

9. A machine having, in combination, a 110 rotary element, actuating mechanism therefor comprising clutch members, a clutch sleeve provided with cams for shifting it 115 from one clutch member to the other, and cooperating pins independently movable into and out of the path of the cams.

10. A machine having, in combination, a 120 rotary element, actuating mechanism therefor comprising clutch members, a clutch sleeve between said members, two rings on the clutch sleeve, cams on the peripheries of the rings, two pins arranged to alternately ride on the corresponding rings to shift the clutch sleeve and then to advance inside the rings to lock the clutch sleeve in shifted position, and means for alternately advancing and retracting the pins.

MAX C. MILLER.
